UNITED STATES PATENT OFFICE.

FRANK RHIND, OF MERIDEN, CONNECTICUT, ASSIGNOR OF ONE-HALF TO
EDWARD MILLER & COMPANY, OF SAME PLACE.

HANGING LAMP.

SPECIFICATION forming part of Letters Patent No. 394,882, dated December 18, 1888.

Application filed May 31, 1888. Serial No. 275,616. (No model.)

To all whom it may concern:

Be it known that I, FRANK RHIND, of Meriden, in the county of New Haven and State of Connecticut, have invented a new Improvement 5 in Hanging Lamps; and I do hereby declare the following, when taken in connection with accompanying drawings and the letters of reference marked thereon, to be a full, clear, and exact description of the same, and which 10 said drawings constitute part of this specification, and represent, in—

Figure 1, a side view of a hanging lamp complete, a portion of the hanger broken away to show the application of the invention; 15 Fig. 2, a sectional side view of the hanger and the suspending-loop and the chains, enlarged, this being the upper portion of the fixture, section cutting on line *x-x* of Fig. 3; Fig. 3, a top view of the same; Figs. 4 and 5, transverse sections of the same, illustrating the operation of the cam upon the brake-bar; Figs. 6, 7, 8, 9, and 10, modifications of the invention.

This invention relates to an improvement 25 in that class of hanging lamps in which a hanger is applied to a hook or other device in the ceiling as a means for suspending the lamp.

The lamp is carried in a frame below, and 30 two or more chains are attached by one end to the lamp support or frame and run up over corresponding pulleys in the hanger, thence down, their other end attached to a counterbalancing-weight, and so that as the 35 lamp-frame is drawn downward the weight will rise, and vice versa. This is a common construction of hanging lamps. It is necessary that the weight shall so counterbalance the lamp and its support that the lamp may be 40 adjusted to different elevations; but, owing to the fact that the oil in the lamp is consumed, the weight of the suspended portion of the fixture will be constantly diminishing, so that if the weight counterbalance the adjustable 45 portion of the fixture when the fount is filled, when the fount is empty the weight will be too heavy, and naturally draw the said adjustable portion to its highest elevation. Again, the weight of founts and of the adjustable 50 portion of the fixture varies to a consider-

able extent, and this variation is increased by the absence or presence of shades. To provide for this variation, devices have been provided to apply friction to the pulleys over which the chains run, or in some cases directly 55 to the chains. This friction is constant, and must be sufficient to provide for the greatest possible variation in the weight of the suspended portion of the fixture, and that friction must be overcome both in drawing down 60 and raising the said adjustable part. Many times this friction interferes materially with the free working of the adjustable part of the fixture.

The object of my invention is to provide a 65 brake which may be operated through the lamp-support itself.

In another application, Serial No. 268,527, filed March 26, 1888, I have illustrated and described an invention for applying a brake 70 or lock to a spring-drum, from which the lamp-supporting frame is suspended by two or more chains wound upon the drum. In that invention the brake is operated by imparting a rotation to the lamp-supporting frame pre- 75 paratory to drawing down or raising that frame.

In the present invention I take advantage of the same rotation of the lamp-supporting frame to operate the brake upon pulleys or 80 chains of a weight-supported hanging lamp; and the invention consists in a hanger carrying two or more pulleys, over each of which chains run from the lamp-supporting frame, their free ends connected to a weight or 85 weights below the hanger, combined with a vertical spindle, upon which said hanger may rotate in a horizontal plane, the said spindle provided with an eye or hook as a means for suspending the lamp, which eye or hook is 90 prevented from rotation, with a brake adapted to be applied to the pulleys carrying the chains, or directly to the chains by a rotation of the hanger independent of the suspending-loop, as more fully hereinafter described. 95

A represents the hanger, in which two or more pulleys, B, are hung upon an axis, and so as to revolve in a vertical plane, and as usual in this class of fixtures.

C represents the lamp-supporting frame, 100

which carries the fount D, and also, as here represented, carries the shade E. From the lamp-supporting frame two or more chains, according to the number of pulleys, (here represented as two, F G,) are connected by one end to the lamp-supporting frame directly or indirectly, and extend up over said pulleys B B, thence down. They are connected by their other ends to a weight, H, the said weight serving to counterbalance the adjustable portion of the fixture in the usual manner, and so that as the said adjustable portion is raised the weight drops accordingly, or vice versa.

So far the construction is common and well known.

I represents a vertical spindle arranged concentrically in the hanger, and which serves to support the hanger. The spindle at its upper end is provided with an eye or hook, J, by which it may be attached to a corresponding loop or hook in the ceiling, and so that the said connection with the ceiling will prevent the rotation of the hook or eye J; but the hanger is made free to rotate upon the spindle independent of the suspending-loop, and so that by taking hold of the supporting-frame below and imparting a rotation thereto rotation will be communicated to the hanger through the chains and in either direction, according as the frame is rotated.

K represents a bar, which extends across the hanger, its ends resting upon the pulleys B B, respectively, as seen in Figs. 2 and 3. An opening is made through the bar, through which the spindle I passes, and the bar is held by guides *aa*, which extend up from the hanger, so that the bar will rotate with the hanger independent of the suspending-loop, and consequently always rest upon the pulleys. The base of the loop is enlarged above the bar, and is constructed with a cam-shaped under surface, *b*, which works upon the bar, and so that as the hanger and bar are rotated in one direction the cam-surface will operate upon the bar to force it upon the pulleys and produce friction thereon accordingly, or, rotated in the opposite direction, will take the bar from the bearing portions of the said cam and remove the friction from the pulleys. These movements of the bar are indicated in Figs. 4 and 5, Fig. 4 showing the bar as under the influence of what may be called the "rise" of the cam, and therefore applying the friction; and Fig. 5 shows the bar as standing in the depression of the cam when the friction is removed.

When the fixture is suspended in the usual manner from the ceiling, the loop J being held thereby, so as to prevent its rotation, as before described, and the rise of the cam operating upon the bar K, sufficient friction is produced to prevent the rotation of the pulleys. Consequently the friction of the chains upon the pulleys will be so great as to prevent any accidental movement of the chains.

When it is required to adjust the elevation of the lamp, the hand is applied to the lamp-

supporting frame and a partial rotation imparted to it, which is communicated to the hanger through the chains, as indicated in broken lines, Fig. 3, which rotation takes the brake-bar K into the depression of the cam on the loop, and thereby removes the pressure of the brake upon the pulleys. Now the pulleys are free, the lamp may be raised or lowered, as desired, and when the desired position is attained the lamp-frame is rotated in the opposite direction. That rotation being communicated to the hanger, as before, brings the brake-bar upon the rise of the cam, and the power of the brake will be applied as before, and hold the lamp suspended at that point.

It will be evident that the friction may be applied to a weighted suspension-lamp in various ways by the rotation of the hanger under a corresponding rotation of the supporting-frame through the chains connecting said frame with the hanger. To illustrate other and analogous devices for so applying the friction, I represent in Fig. 6 the spindle I as constructed with a screw-thread, L, which works through a corresponding screw-thread in the brake-bar K, and so that under the rotation of the hanger, as before described, the said bar will work upon the screw-thread L on the spindle, which is stationary, as before, and will impart an up or down movement to the brake-bar, according to the direction in which the hanger is rotated.

Instead of applying a single brake-bar to operate upon both pulleys, the brake K may be made in two parts, as seen in Fig. 7, each part hinged to the hanger, so as to swing up and down upon the pulleys, the enlargement or base of the loop J being sufficient to extend over the inner ends of the brakes, and constructed upon its under surface with substantially the same rise and fall to form the cams *b*, as indicated in Fig. 7, and so that, the loop J with its cams being held stationary, the brake will be applied or removed by the rotation of the hanger from the frame below in substantially the same manner as before described; or the brake-bar K may be made to operate upon brakes hinged to the hanger, as seen in Fig. 8, M representing such brakes hinged to the hanger on the inner side of the pulleys, the brake-bar brought to bear thereon. The brake may be made in the form of a disk made fast to the spindle I, as seen in Fig. 9, this disk being an equivalent for the brake-bar. K in this figure indicates the disk, which, as here represented, is arranged upon the under side of the hanger, and its edge is made cam-shaped, as represented in Fig. 10, the rise of the cam being adapted to bear forcibly against the chains, while the depression of the cam will leave the chains free. The rotation of the hangers in this case is the same as before, to bring the chains into engagement with the respective rise or projecting points of the cam or into the depressions of the cam, as the case may be.

When the fixture is suspended in the usual manner from the ceiling, the loop J being held thereby, so as to prevent its rotation, as before described, and the rise of the cam operating upon the bar K, sufficient friction is produced to prevent the rotation of the pulleys. Consequently the friction of the chains upon the pulleys will be so great as to prevent any accidental movement of the chains.

It will be evident that the brakes may bear directly upon the pulleys or chains with the same result. I therefore do not wish to be understood as limiting the operation of the 5 brake to the pulleys directly.

The screw-thread on the spindle or suspension device is to be understood as a well-known equivalent for the stationary cam.

The hanger may be of any of the usual 10 constructions, and, as usual, is sometimes made from cast metal and sometimes from sheet metal, the outer surface being ornamented to give it a tasteful appearance.

The spindle is preferably made as a permanent or integral part of the suspending-loop; but it may be made a separate piece, as represented in Fig. 7. The spindle in this case, however, forms the axis upon which the 15 hanger turns, substantially as if the spindle 20 be made an integral part of the loop, as in the other illustrations.

I represent one well-known form of counterbalancing-weight, for which it will be understood that other known weights may be 25 substituted.

In some classes of fixtures the weight is the shade or lantern. By the term "weight," therefore, I wish to be understood as including any of the known counterbalancing 30 devices.

I claim—

1. In a hanging-lamp fixture, the combination of a hanger carrying two or more pulleys, a suspending device adapted to be secured to the ceiling and carrying a vertical 35 spindle, the said hanger arranged upon said spindle, and so as to receive a rotative movement independent of the suspending device, two or more pulleys arranged in said hanger, 40 a lamp-carrying frame below, chains attached by one end to said lamp-carrying frame, running upward and over said pulleys, thence

down, a weight attached to the other end of said chains, and so that the said rotation may be imparted to said hanger by said lamp-carrying frame through the said chains, and a brake 45 between said pulleys or chains and the said suspending device, substantially as described, and whereby the said rotation of the said hanger from the lamp-carrying frame through 50 the chains and independent of said suspension device will apply the said brake to or remove it from the said chains or pulleys, according to the direction of such rotation.

2. In a hanging-lamp fixture, the combination of a hanger carrying two or more pulleys, a suspending device adapted to be secured to the ceiling and carrying a vertical spindle, the said hanger arranged upon said spindle, and so as to receive a rotative movement independent of the suspending device, two or more pulleys arranged in said hanger, 55 a lamp-carrying frame below, chains attached by one end to said lamp-carrying frame, running upward and over said pulleys, thence 60 down, a weight attached to the other end of said chains, and so that the said rotation may be imparted to said hanger by said lamp-carrying frame through the said chains, one or 65 more brakes arranged upon the hanger so as 70 to rotate with it, and adapted to operate upon one or more of the pulleys or chains, and a cam on the suspension device and stationary therewith, said cam adapted to operate upon 75 said brake, substantially as described, and whereby, under the rotation of the said hanger in one direction, the said stationary cam serves to apply the brake and rotation in the opposite direction will relieve the brake.

FRANK RHIND.
